BRUSH

Albert R. Racicot, Aurora, Ill., assignor to National Brush
Company, Aurora, Ill., a corporation of Illinois

Application July 7, 1954, Serial No. 31,303

Term of patent 14 years

(Cl. D9—2)

The dominant features of my design reside in the portion shown in full lines.

I claim:

The ornamental design for a brush, substantially as shown and described.
